(57) CLAIM

The ornamental design for a table top, as shown and described.

DESCRIPTION

FIG. 1 is a perspective view of a table top in accordance with a preferred embodiment of the present invention, the perspective view being from an upper, front, left view of the table top;

FIG. 2 is another perspective view of the table top shown in FIG. 1, the perspective view being from an upper, rear, right view of the table top;

FIG. 3 is another perspective view of the table top shown in FIG. 1, the perspective view being from a lower, front view of the table top;

FIG. 4 is a right side view of the table top shown in FIG. 1;

FIG. 5 is a left side view of the table top shown in FIG. 1;

FIG. 6 is a top view of the table top shown in FIG. 1;

FIG. 7 is a front view of the table top shown in FIG. 1; and,

FIG. 8 is a rear view of the table top shown in FIG. 1.

The broken lines are for environmental purposes only and form no part of the claimed design.
